M. MEYERSON
CARD HOLDER.
APPLICATION FILED OCT. 26, 1917.

1,366,818.

Patented Jan. 25, 1921.

UNITED STATES PATENT OFFICE.

MAX MEYERSON, OF NEW YORK, N. Y.

CARD-HOLDER.

1,366,818.

Specification of Letters Patent. Patented Jan. 25, 1921.

Application filed October 26, 1917. Serial No. 198,584.

To all whom it may concern:

Be it known that I, MAX MEYERSON, residing at New York, in the county of New York and State of New York, have invented 5 certain new and useful Improvements in Card-Holders, of which the following is a specification.

This invention relates to a card holder such as may be used upon packages, boxes, 10 trunks, and the like, and the object of the invention is to provide a holder which may be permanently fixed to the package and which is adapted to carry an address or like card, in such a manner that the card 15 may be inserted and removed at will, and to provide the holder with means to positively retain the card against accidental displacement.

A further object is to provide the body 20 part of the holder with a well defined guide-way along which the card may be slid into and out of operative position, and to provide a card retaining member connected with the body part adapted to move from 25 a retaining position obstructing the guide-way to a non-retaining position entirely free of the guide-way.

A further object is to provide means for latching the retaining member against accidental movement out of retaining position.

A further object is to so mount the retaining member that it will be frictionally yieldingly held in any position to which it may be moved.

Other objects and aims of the invention, 35 more or less specific than those referred to above, will be in part obvious and in part pointed out in the course of the following description of the elements, combinations, 40 arrangements of parts and applications of principles, constituting the invention; and the scope of protection contemplated will be indicated in the appended claims.

In the accompanying drawings which are 45 to be taken as a part of this specification, and in which I have shown merely a preferred form of embodiment of the invention:

Figure 1 is a perspective view of a package 50 illustrating the card holder of this invention as in use applied thereto.

Fig. 2 is a plan view of the card holder detached, illustrating a card retained therein.

55 Fig. 3 is a transverse sectional view taken upon the plane of line III of Fig. 2.

Fig. 4 is an enlarged fragmentary view showing the manner in which the card retaining member is mounted and operated, and

60

Fig. 5 is a fragmentary perspective view illustrating a modified construction.

Referring to the drawings for describing in detail the structure which is illustrated therein, the reference character L indicates 65 the main or body portion of the card holder. This comprises upper and lower members 1 and 2 and an end member 3, all connected together and preferably stamped from a single sheet of suitable material such as 70 sheet metal or the like. The end opposite to the member 3 is left open and the inner edge portions of the members 1, 2 and 3 are off-set as at 4, to provide a groove or guide-way 5 beneath them. The card, as G, is intended to be slid into and out of the guide-way 5 through the open end opposite to the member 3.

The body member may be permanently and rigidly connected to the surface of the 80 package, box or other article, as 6 (Fig. 1) by means of rivets or other fastening means 7.

The card retaining member, as H, is adapted to move into and out of position 85 closing the open end of the guide-way, and, as an exemplary way of so mounting the retaining member, it is shown to be pivotally connected to the member 1 of the body. For this purpose its upper end is 90 forced under the end portion of the member 1 and is pivotally connected thereto as by a pivot member 8. The lower or free end of the retaining member may be squeezed into and out of position beneath 95 the adjacent end portion of the member 2 of the body.

Frictional engagement of the card retaining member with the under surfaces of the adjacent end portions of the members 1 and 100 2 may be sufficient to hold the card retaining member against accidental opening movement, but preferably a positively acting latch member, as 9, is employed. The latch member shown is made of a small 105 piece of spring material. It is connected with the card retaining member and is provided with a head 10 arranged to enter an opening 11 formed in the member 2 and to engage behind a shoulder 12 of said opening 11 when the card retaining member is fully closed. Before the card retaining

110

member can be swung open the head 10 may be pressed downwardly by the operator's finger so as to disengage from the shoulder 12.

5 The retaining member is preferably fitted with an off-set portion 13 to correspond with the off-set portions 4 of the body part, the off-set portion 13 being intended to stand in position over the adjacent edge of 10 the card after the card has been slid into the guide way 5 as clearly seen in Fig. 2.

The pivotal mounting of the card retaining member is such that when said member is moved to the open position no part thereof 15 obstructs free movement of the card into and out of the guide-way 5.

As suggested by the lettering appearing upon the card in Fig. 2, this holder may be very advantageously used for retaining 20 cards which may be reversed from time to time, that is, with a card bearing a forwarding address on one side and a returning address on the other side, the same card may be used to carry the package to its 25 first destination and then reversed to carry the package back to its original holder. Packages of articles to be washed, for instance, may be sent to the laundry, and returned to the owner, with the least possible 30 confusion.

In the modification Fig. 5, a structure is illustrated which differs from that of the previous figures only in that the off-set portions 4 and 13 are formed by building up 35 the parts of the device from pieces, or strips, laid one upon the other, the inner edges of the underlying strips as 14, in each case being inset with respect to the inner edges of the overlying strips 15 so as to 40 form the guide-way 5. This arrangement also readily provides recesses, as 16, beneath which the ends of the card retaining member are received.

The structure shown in Fig. 5, also has 45 a certain advantage over the structure shown in the other figures, in that it enables the use of scrap strips of material, such as sheet fiber, and avoids necessity for the use of the expensive dies which would 50 be necessary to shape up the parts as in the other figures. In a factory where boxes and cases are being manufactured, card holders constructed as in Fig. 5, may, therefore, be formed and attached to the cases at extremely 55 small cost.

As many changes could be made in this construction without departing from the scope of the invention as defined in the following claims, it is intended that all matter 60 contained in the above description or shown in the accompanying drawings shall be interpreted as illustrative only and not in a limiting sense.

Having thus described my invention, what

I claim as new and desire to secure by Letters Patent is:—

1. A card holder adapted for attachment to the surface of an article for retaining a card affixed to said article, said card holder comprising a body member and a retaining member to retain the card within the body member, the body member being substantially of U-shape in general contour and being of a cross section to provide relatively outer marginal portions adapted for attachment to the surface of the article and relatively inner marginal portions disposed to stand away from the underlying surface portions of the article so as to provide a guide-way between themselves and the article to receive marginal portions of the card, the retaining member comprising a strip of material having one of its ends pivotally connected to one leg of the U, the opposite end of said strip of material being adapted to swing into and out of position between the end portion of the other leg of the U and the underlying portion of the surface of the article, and a latch device co-operative between said last mentioned portions of the body member and the retaining member to hold the retaining member against accidental opening movement out of retaining position.

2. A card holder comprising a plurality of strips of sheet material, said strips being arranged upon the surface of an article for retaining a card fixed to said surface of the article, the strips being connected with the article so that certain of said strips of greater width overlie others of said strips of lesser width thus providing portions of the first mentioned strips overhanging the second mentioned strips and spaced from said surface of the article, the disposition of the strips being such as thereby to provide a pocket within which a card may be retained flat upon the surface of said article, and a further strip having one of its ends pivotally engaged between an overhanging portion of one of the superposed strips and the underlying portion of the article and having its opposite end disposed to swing about said pivot into and out of position between an overhanging portion of another of said superposed strips and the adjacent underlying portion of the article to thereby serve as a removable retaining member for the card.

3. A card holder comprising a plurality of strips of sheet material, said strips being arranged upon the surface of an article for retaining a card fixed to said surface of the article, said strips being connected with the article so that certain of said strips overlie others of said strips, portions of the first mentioned strips overhanging the second mentioned strips and spaced from said sur-

face of the article, the disposition of the strips being such as thereby to provide a pocket formed partly by the surface of said article and partly by said strips within 5 which pocket a card may be retained flat upon the surface of said article, and a further strip disposed to form a closure for said pocket.

4. A card holder comprising a plurality 10 of strips of sheet material, said strips being arranged upon the surface of an article for retaining a card fixed to said surface of the article, said strips being connected with the article so that certain of said strips of 15 greater width overlie others of said strips of lesser width, thus providing portions of the first mentioned strips overhanging the sec-

ond mentioned strips and spaced from said surface of the article, the disposition of the strips being such as thereby to provide a 20 pocket formed partly by the surface of said article and partly by said strips within which pocket a card may be retained flat upon the surface of said article, and a further strip disposed to form a closure for said 25 pocket, together with means whereby to facilitate convenient removal of the card from the pocket.

In testimony whereof I affix my signature in the presence of two witnesses.

MAX MEYERSON.
